UNITED STATES PATENT OFFICE.

WILLIAM H. ROCHE AND FREDERICK F. PONTIUS, OF BUFFALO, NEW YORK.

DOOR-ALARM.

1,123,802.

Specification of Letters Patent.

Patented Jan. 5, 1915.

Application filed September 30, 1912. Serial No. 723,224.

To all whom it may concern:

Be it known that we, WILLIAM H. ROCHE and FREDERICK F. PONTIUS, citizens of the United States of America, residing at Buffalo, in the county of Erie and State of New York, have invented certain new and useful Improvements in Door-Alarms, of which the following is a full, clear, and exact description.

10 Our invention relates to burglar alarms, and more particularly to detonating alarms.

The general object of our invention has been to provide an alarm of this character which can be used on sliding doors and one 15 which may be operatively set before the door is closed, without danger of tripping or discharging the same.

Another object has been to provide a device, the tripping mechanism of which, shall be set in its operative position by the closing of the door.

Another object has been to provide a device which shall be cheap to manufacture, of few parts, and easily installed.

25 Reference is to be had to the accompanying drawings, forming part of this specification, in which like characters of reference indicate like parts throughout the several views of which:

30 Figure 1 is a plan view of the tripping mechanism of our device, showing the trip arm of the same in the position occupied when closing the door. Fig. 2 is a side elevation of the same and shows the trip arm in its operative position. Fig. 3 is a side elevation of the discharge mechanism of our device, and shows the hammer thereof in its operative position. Fig. 4 is a plan view of the discharge mechanism of our device.

40 Fig. 5 is a perspective view of our device attached to a sliding door and shows it set in its operative position.

Referring now to Figs. 3 and 4 which show the discharge mechanism of our device, 10 is the base thereof which is provided at one end with an upward right-angled bent portion 11. 12 is the cartridge anvil, which is preferably secured to the bent portion 11 and the base 10. Through 50 the anvil 12 and the bent portion 11 is provided an aperture in which the alarm cartridge 13 is disposed. 14 is a lock plate which is pivotally secured to the anvil at 15 and has its free end disposed behind a lug 16, also carried by said anvil. This lock plate is provided with a central aperture 17

which registers with the center of the cartridge and is adapted to hold the same in its place against the anvil. 37 is a latch plate pivotally secured to the anvil 12 and bent portion 11, which retains the lock plate 14 in its position. 18 is the hammer of the discharge mechanism which is slidably supported in line with the cartridge by the standards 19, 19, which are secured to the base. The hammer 18 is provided at its outer end with a right-angled arm 20 and a cam-shaped trigger arm 21, which is bent so as to lie in a plane at right angles to the arm 20. 22 is a helical spring which is disposed about the hammer 18 and between one of the plates 19 and a pin 23 carried by the said hammer. 24 is a detent pin which is carried by the base 10 and disposed preferably at right angles to the same. This pin 75 is adapted to engage the arm 20 of the hammer when the same is drawn back against the tension of the spring 22, as shown in the drawings.

Referring now to Figs. 1 and 2 where the tripping mechanism of our device is shown, 25 is the base thereof, which is provided with an upwardly bent end portion 26. 27 is a bearing plate which is secured to the base 25 and which is arranged to pivotally carry the lower end of the trip arm 28. 29 is a helical spring which is secured at one end to the upwardly bent portion 26, and at the other end to the trip arm 28, whereby the said trip arm is normally held at right angles to the base 25. 30 is a Z-shaped bearing standard which is secured to the base 25 and which pivotally carries one end of the lock arm 31. This lock arm is arranged to swing in a plane at right angles to the path of rotation of the trip arm and is adapted to hold the said trip arm in its inoperative position, when the sliding door to which our device is attached, is open. 32 is a release rod, which is provided with an enlarged head 33, 100 and which is slidably carried by the upwardly bent end portion 26 and the bearing standard 30. This release rod is normally held in the position shown in the drawings by the spring 34, which is disposed about the same. This rod is so arranged that its rear end is engageable with the lock arm 31.

In Fig. 5 where we have shown our device in position, 35 represents a fragmental portion of a sliding door and 36 a fragmental portion of the casing thereof. As shown in this figure the discharge mechanism of our

device is secured in the position shown, to the casing 36, on the inside of the door. The tripping mechanism is preferably set in the door with the upwardly bent end portion 26 flush with the front edge of the door so that the trip arm will project inwardly when it is in its operative position, as shown in this figure.

When our device has been attached to a sliding door, as for instance, a box car door, and it is desired to load and set the same, a cartridge or percussion cap is placed in the aperture provided through the anvil 12 and bent portion 11 and locked in place. The hammer 18 is then drawn back and the arm 20 thereof hooked over the detent pin 24. This will bring the cam-shaped trigger arm 21 in the path of travel of the trip arm 28 of the tripping device, when said trip arm is in its operative position.

After the discharge mechanism has been loaded and set, the trip arm 28 of the tripping mechanism is pulled down to the position shown by the dotted lines (Fig. 2) and the lock arm made to engage with the same and hold it in place. It is to be seen that when the trip arm is in this position the sliding door may be closed without interference with the discharge mechanism or danger of tripping the same.

When the door has been entirely closed, the head 33 of the release rod will engage with the door jamb and will be pushed back flush with the face of the bent end portion 26 and against the tension of the spring 34. As the release rod is pushed inwardly by the closing of the door, its inner end will engage with the lock arm 31 and move the same substantially to the position shown by the dotted lines in Fig. 1, which releases the trip arm from its inoperative position shown by the dotted lines in Fig. 2, and allow the same to be drawn by the spring 29 to its operative position as shown in Figs. 2 and 5. When the door is then opened by any unauthorized person, the trip arm will engage with the cam-shaped trigger 21 of the discharge mechanism and partially rotate the same, thus releasing it from the detent pin 24 and allowing it to be driven forward under the tension of the spring 22, thereby discharging the cartridge and giving the alarm.

Having thus described our invention, what we claim is:

1. In a device of the character described, the combination with a discharge mecha-

nism having a longitudinally movable hammer provided with a cam-shaped arm, of a door, a tripping mechanism carried by said door and movable longitudinally with said discharge mechanism, said tripping mechanism comprising a base, a trip arm pivotally carried by said base, spring tension means for holding said trip arm in its operative position, a stop for limiting the movement of said trip arm, means for latching the outer end of said trip arm, and means for releasing said trip arm when said door is closed.

2. In a device of the character described, the combination with a discharge mechanism having a hammer provided with a cam-shaped arm, a door and a door jamb, of a tripping mechanism comprising, a base carried by said door, a trip arm pivotally carried by said base, means for keeping said trip arm normally at right angles with said base, a lock arm pivotally carried by said base and adapted to engage the free end of said trip arm, when lying parallel with said base, to hold the same in its inoperative position when closing said door and means carried by said base and engageable with said door jamb, whereby when said door is closed said trip arm will be released and moved into its operative position.

3. In a device of the character described, the combination with a discharge mechanism having a hammer provided with a cam-shaped arm, a door and a door jamb, of a tripping mechanism comprising, a base carried by said door, a trip arm pivotally carried by said base, means for keeping said trip arm normally at right angles with said base, a lock arm pivotally carried by said base and adapted to engage the free end of said trip arm, when lying parallel with said base, to hold the same in its inoperative position when closing said door and a release arm slidably carried by said base and having its outer end engageable with said door jamb and its inner end engageable with said lock arm, whereby when said door is closed, said trip arm will be released and moved into its operative position.

In testimony whereof, we have hereunto signed our names in the presence of two subscribing witnesses.

WILLIAM H. ROCHE,
FREDERICK F. PONTIUS.
